(57) **CLAIM**

The ornamental design for an ear dryer, as shown and described.

DESCRIPTION

FIG. 1 is a perspective view of an ear dryer showing our new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof; and,

FIG. 8 is an enlarged view of the encircled area 8 of FIG. 4. The broken lines shown in the figures depict portions of the ear dryer that do not form part of the claimed design. In FIGS. 4 and 8, the broken lines depict the enlarged view boundaries that do not form part of the claimed design.
